HAROLD E. HALLENBECK, OF HUDSON, NEW YORK, ASSIGNOR TO GIFFORD-WOOD COMPANY, OF HUDSON, NEW YORK, A CORPORATION OF NEW YORK

COMBINED INDICATOR AND LIMIT SWITCH ACTUATOR

Application filed December 12, 1931. Serial No. 580,686.

This invention relates to improvements in limit switches for electrically operated traversing hoists and among other objects, aims to provide a very simple and compact limit switch actuator preferably, but not necessarily, combined with indicating means, and so constructed and arranged that the traverse motor is automatically stopped at the predetermined limits of travel of the load carrier operated by said motor. The invention particularly aims to improve upon known trolley bucket systems by providing a motor control unit of such few parts that it may be manufactured and installed very economically, and hence may be sold at a low price; also to provide a unit rotatable for ease of adjustment and adaptability to various traversing hoist installations. The invention has other objects which will appear during the following description of the preferred embodiment thereof which is shown in the accompanying drawings.

In said drawings,—

Fig. 1 is a plan view of a motor-powered traversing hoist unit equipped with an actuator for limit switches;

Fig. 2 is an elevation, on a somewhat larger scale, of the mechanism for driving the limit switches and indicating means;

Fig. 3 is a side elevation of the mechanism of Fig. 2; and

Figs. 4 and 5 are vertical sections, at right angles to each other and both on the same enlarged scale, of the limit switch casing and actuating parts.

The motors of the described power unit are preferably used in an automatic electric control system such as is described and claimed in my pending application, Ser. No. 491,534, filed October 27, 1930; although the invention will be equally useful in a trolley bucket system controlled by hand. The wiring and connections are such that the bucket is automatically hoisted, when loaded, to a point adjacent the underside of the trolley, whereupon hoisting automatically stops and traverse movement in a predetermined direction begins. When the trolley has reached a point over the spot where the load of the bucket is to be discharged, it is automatically

stopped, and lowering of the bucket automatically takes place. Dumping of the contents of the bucket is effected as soon as the bucket strikes an obstruction, as disclosed in the Bennett Patent No. 1,741,123 of December 24, 1929, and substantially instantaneous reversal of the bucket takes place, so that the bucket starts up to the trolley as its load discharges. As soon as the bucket reaches the trolley, hoisting automatically ceases, traverse begins and continues until the trolley is over the point where the bucket is to be lowered for another load; then traverse is stopped, the bucket is automatically lowered and brought to a stop at the loading point.

Referring particularly to Fig. 1, there is shown a machine base 10 on which all the parts to be described are supported, so that the entire mechanism may be shipped and installed as a unit. Journalled in bearings 11 secured to the frame is a drum-shaft 12 on which hoist drum 13 and trolley or traverse drum 14 are mounted for independent rotation. Hoist drum 13 is loose on shaft 12 and is driven by a gear 15 fixed thereto and meshing with a pinion 16 on a countershaft 17 journalled in bearings 18. Countershaft 17 is driven by a gear 19 which meshes with motor pinion 20 of the hoist motor 21 which is on base 10. Obviously rotation of the hoist motor in opposite directions will drive hoist drum 13 in opposite directions at a reduced speed, thereby winding or unwinding hoist cable 22 (which is dead-ended to the drum) to raise or lower the bucket or other load carrier, not shown.

The traverse or trolley drum 14 is fixed on shaft 12 and hence is rotated by gear 23 which is secured to said shaft. Gear 23 is driven by pinion 24 which is secured to gear 25 loosely mounted on countershaft 17, and gear 25 is driven by pinion 26 of the traverse or trolley motor 27 mounted on the base 10. Reverse rotation of motor 27 will obviously rotate drum 14 in opposite directions, at a reduced speed, to move the traverse cable 28 in opposite directions. On the shafts of the motors 21, 27 are solenoid brakes 29, 30 respectively, said brakes acting automatically to stop the motors and hence the drums and

cables whenever the power is cut off from the motors. In the aforesaid pending application, I have shown means whereby power is automatically cut off from and applied to the 5 motors at the proper intervals.

As shown in Fig. 1, there is a sheave 31 mounted to rotate in a vertical plane on a sheave stand 32 secured to machine base 10, and the traverse or trolley cable 28, after being wrapped several times about drum 14, 10 is passed around sheave 31 and brought back around the drum 14 again. The cable 28 extends upwardly to the trolley (not shown) to which its ends are fixed, so that rotation 15 of drum 14 in opposite directions will move the trolley in opposite directions, thus moving the bucket, which is suspended from the trolley by the hoist line. It will be clear that the trolley is moved solely because of friction 20 between the cable 28 and drum 14. This friction is enhanced by wrapping the cable 25 around sheave 31 and then bringing it back to and around the drum, as the cable tends to hug the drum more tightly when passed at an intermediate point around a sheave spaced from the drum shaft but parallel to the medial plane of the drum.

The sheave 31 is not only useful for increasing the frictional grip of the traverse cable on its drum; it is also used to drive the 30 indicator (to be described) which shows the position of the trolley and also the limit switch mechanism (to be described) which controls two limit switches governing the 35 traverse of the trolley through its motor 27. As the cable 28 drives sheave 31 by friction only, and as said cable is directly secured at both ends to the trolley, it follows that only 40 actual movement of the trolley effects movement of the trolley indicator and of the trolley-governing limit switch actuating mechanisms, which are driven only when sheave 45 31 is rotated. Therefore, slippage of the drum 14 relative to cable 28 may take place 45 without affecting the accuracy of the indicator and without affecting the proper working (in point of time) of the limit switches.

Only slippage or movement of cable 28 relative to sheave 31 would make the indicator and limit switches inaccurate, and such slippage or relative movement will not occur except under extraordinary circumstances because the load on sheave 31 is very light, and cable 28 presses against it very tightly. 50

Referring to Figs. 2 and 3, which best show the indicator, it is seen that sheave 31 drives a shaft 33 on which there is a bevel gear 34 meshing with bevel gear 35 on a vertical shaft 36. While an idler or rope 55 driven sheave 31 is greatly to be preferred, for the illustrative traversing hoist unit, it is within the scope of my invention to provide a gear drive for shaft 33, and hence for shaft 36, which may be done whenever 60 the load carrier has no slippage relative to

the drum which operates it, for example, when the indicator and limit switches are to be used with a hoist drum. The vertical shaft 36 is enclosed in a tubular housing 37 supported by a bracket 38 on the upper end 70 of sheave stand 32, and said housing 37 provides a standard, fixed upon the machine base, by which the indicator or dial plate 39 and limit switch housing 40 are supported. See, also, Fig. 1. Through a reduction 75 gearing, to be described, vertical shaft 36 drives a horizontal shaft 41 on which a pointer 42 is fixed, the pointer thus rotating slowly in one direction or the other as the trolley moves back and forth on its track. 80 By selecting the proper reduction gearing and arranging the indicia 43 properly, it is clear that the position of the bucket may be ascertained at any time in its traverse by noting the pointer's position relative to 85 the dial.

Obviously, in the described embodiment, the pointer will rotate not more than one revolution for the greatest possible traverse of the bucket from the loading point; but if 90 desired, the indicator may be of a different type, as like the indicator of the H. V. Hard- 95 ing Patent No. 1,705,973 dated March 19, 1929, in which event the speed reduction need not be so great, and traverse over a large plant may be accurately indicated. For small plants, however, the described embodiment is ideally fitted, as it is quite economical to make, install and maintain in service. As shaft 41 is also a limit switch 100 actuating shaft, it follows that the only extra parts necessary for the indicator are the pointer 42 and dial 39.

At the upper end of standard 37, a collar 44 fitting over said upper end is secured by a set screw 45 (Figs. 2 and 3), said collar thus permitting rotation of the indicator assembly to turn the dial toward the operator's position, whatever it may be. Thus the indicator is adaptable to a wide variety of 110 conditions without any change in its construction.

Referring to Figs. 4 and 5, it is seen that the upper end of vertical shaft 36 is within the housing 40 and carries a worm 46 meshing with worm gear 47 fast on shaft 41, the pointer 42 being secured to shaft 41 by a nut 48 and by parts to be described. Obviously, at the start of traverse, the pointer should be at the zero position, but if not, the sheave 31 is rotated by hand, with cable 28 stationary, until the pointer is exactly at the zero mark. Thus the indicator may be set accurately without difficulty. 115

Within the casing or housing 40 are two limit switches 49 of standard construction, being supported by bracket 50 in such position that their pivoted switch arms 51 are moved by cams 52 which are fast to shaft 41. Preferably the cams 52 are of bakelite 120 125

or other insulating material, so that there is no possibility of grounding the limit switches through the indicator standard. The pivoted switch arms 51 are held pressed against the switch contacts 53 by springs 54 except when the cams 52 push them away from the contacts, against the resistance of the springs, thus breaking the circuit of the traverse motor. Each switch arm is insulated from the bracket 50 and the casing 40 and has a contact 51 which touches one of the adjustable contacts 53 when the circuit controlled by said switch arm is closed. Contacts 53 are screw-threaded for adjustment, so that the circuit may be properly broken by each cam. Further details of the limit switches are not disclosed because the specific construction of said switches forms no part of my invention.

As shown, shaft 41 is journaled in a U-shaped bearing bracket 55 secured to the bottom of housing 40. Each cam 52 is angularly adjustable upon and is secured to shaft 41 by means which will now be described. Referring to the left hand cam in Fig. 5, there are screws 56 secured to said cam and passing through spacing members 57, 58, being parallel to shaft 41. Shaft 41 carries two bushings 59, 60, bushing 59 being fixed to the shaft and bushing 60 being loose upon it, and both bushings having a circular end flange. The flange of bushing 59 may serve to space cam 52 (which surrounds said bushing) from the adjacent wall of the bearing bracket 55, as shown, thus preventing movement of the cam in one direction on the shaft; the spacing members 57, 58 and nut 48 preventing movement in the opposite direction. It will also be clear that shaft 41 is prevented from moving longitudinally in one direction by the end flange of bushing 59. The flange of bushing 60 not only provides an abutment for the outside spacing member 58 but also provides convenient means for securing the pointer 42 to bushing 60, this being done by screws 61. Both bushings are cut away at their meeting ends, as clearly shown, so that bushing 60 may be locked against rotation relative to bushing 59 (and hence relative to shaft 41) whenever said ends engage in the manner illustrated. Such engagement is effected by tightening nut 48, which thrusts bushing 60 along shaft 41 toward bushing 59. However, the angular position of the cam with respect to shaft 41 may be changed at any time by loosening nut 48, whereupon the assembly consisting of the two spacing members 57, 58 and cam 52 may be turned on said shaft. This operation obviously varies the time at which the left-hand limit switch will operate, and hence varies the amount of traverse of the load carrier in one direction.

Referring now to the construction at the right side of Fig. 5, it will be clear that the right-hand cam 52 is adjustable relative to

shaft 41 in the same manner as the left-hand cam. A short pointer 62 is clamped by nut 63 to the shaft, just as the long pointer 42 is. This short pointer provides a convenient means for determining the adjustment which has been made at the other side of the casing and will enable the operator to duplicate the adjustment on the right-hand side. The position of pointer 62 may be marked by using a sharp implement on spacing member 58, or said member may be initially marked with indicia, not shown. Thus both cams may be moved angularly as often as desired, until it is determined by experiment that they actuate the limit switches to bring the trolley to a stop at the proper point. Obviously, the adjustment of both cams is very quickly and easily effected.

The described construction is an easily installed and adjusted and economical combined indicator and limit switch actuator for a small trolley bucket plant.

Obviously, the present invention is not restricted to the particular embodiment thereof herein shown and described. Moreover, it is not indispensable that all the features of the invention be used conjointly, since they may be employed advantageously in various combinations and sub-combinations.

What I claim is:—

1. A combined actuator for limit switches and for an indicator comprising, in combination, a shaft driven through a reduction gearing; a pointer on the shaft; a pair of limit switches adjacent the shaft; a pair of cams carried on the shaft in position to actuate said limit switches; and means on the shaft to hold the pointer and also the cams immovable relative to the shaft, said means being disengageable to permit angular adjustment of each cam and also the pointer relative to the shaft.

2. A combined actuator for limit switches and for an indicator comprising, in combination, a driven shaft; a worm on said shaft; a worm gear driven by said worm; a second shaft driven by said worm gear; said second shaft being screw-threaded at its opposite ends; a nut on each end of the second shaft; a pair of limit switches adjacent the second shaft; a pair of spaced cams carried on the second shaft in position to actuate said limit switches; a pair of pointers also on said shaft; and means on the shaft providing abutments against which the two cams and the two pointers may be pressed so as to clamp them to the shaft whenever said nuts are tightened.

3. A combined actuator for limit switches and for an indicator comprising, in combination, a driven shaft; a worm on said shaft; a worm gear driven by said worm; a second shaft driven by said worm gear; said second shaft being screw-threaded at its opposite ends; a nut on each end of the second shaft;

- a pair of limit switches adjacent the second shaft; a pair of spaced cams carried on the second shaft in position to actuate said limit switches; a pair of pointers also on said shaft; 5 two pairs of bushings on the second shaft, the two inner bushings having end flanges providing abutments for the cams and the two outer bushings providing means for securing the pointers; and spacing members loose on the second shaft and interposed between the cams and the outer end flanges; the inner bushings being fast to the shaft and the outer bushings being interlocked with the inner bushings when the nuts are tightened.
- 10 15. An actuator for limit switches and for an indicator comprising, in combination, a shaft; means for driving the shaft at a very slow speed; a pair of bushings fixed to the shaft and having flanges at their inner ends; 20 a pair of cams loose on said shaft, surrounding said bushings, and abutted against said flanges; a second pair of bushings slidable on said shaft but interlocked with the first pair so that they rotate with the shaft, when 25 in position; nuts screw-threaded on the opposite ends of said shaft; and pointers secured to the outer ends of the second pair of bushings, with the nuts located outside said pointers, so as to thrust said second bushings inwardly when tightened.
- 30 35. An actuator for limit switches comprising, in combination, a shaft; means for driving the shaft at a very slow speed; a pair of cams at spaced points on said shaft; a pair of bushings secured to the shaft with the cams surrounding them; a second pair of bushings on the shaft interlocked with the first pair of bushings yet removable therefrom by pulling longitudinally of the shaft; a pair of nuts 40 screw-threaded on opposite ends of said shaft; said nuts, when tightened, thrusting the second pair of bushings into interlocking engagement with the first pair; said cams being individually clamped to the shaft when 45 the corresponding nuts are tightened.
- 50 55. An actuator for limit switches comprising, in combination, a casing; a U-shaped bearing bracket intermediate two opposite walls of the casing; a shaft rotatably supported by said bearing bracket; a worm gear fixed to the shaft between the two arms of said bearing bracket; a power-actuated worm for driving said worm gear; bushings fixed to said shaft on each side of the bearing bracket and each having an end flange abutting against the outer wall of the bearing bracket; a cam loosely surrounding each of said bushings; spacing means outside of each cam but loose on said shaft; and nuts screw-threaded on each end of the shaft and clamping said cams on the shaft by thrusting the same, through the spacing means, against the aforesaid end flanges.
- 60 65. A unitary indicator comprising, in combination, a sheave; a sheave stand; a vertical

shaft supported by the sheave stand and driven by the sheave; a standard enclosing said shaft and supported by the sheave stand; a worm on the upper end of the vertical shaft; a worm gear driven by the worm; a horizontal shaft driven by the work gear; a dial plate secured to said standard; and a pointer fixed to said horizontal shaft and movable over the face of the dial plate.

70 8. A unitary indicator comprising, in combination, a sheave; a sheave stand; a vertical shaft supported by the sheave stand and driven by the sheave; a standard enclosing said shaft and supported by the sheave stand; a casing rotatably supported at the top of said standard; a worm on the upper end of the vertical shaft, within said casing; a worm gear within the casing driven by said worm; a dial plate fixed to said casing on the outside; a horizontal shaft driven by said worm gear; and a pointer fixed to said horizontal shaft and movable on the face of the dial plate.

85 9. A unitary indicator comprising, in combination, a vertical standard; a power-driven shaft within the standard; a casing; a collar fixed to the underside of the casing and rotatably mounted on the upper end of the standard; a set screw holding the collar and casing in any desired angular position; an indicator dial fixed to the casing; reduction gearing within the casing driven by said shaft; a second shaft within the casing driven at a slow speed by said reduction gearing; and a pointer secured to said second shaft and movable over said dial.

90 In testimony, that I claim the foregoing as my own, I have hereto affixed my signature.
